UNITED STATES PATENT OFFICE.

FRANK NOSSEK, OF CHICAGO, ILLINOIS.

APPARATUS FOR COMPACTING CONCRETE OR THE LIKE.

Application filed November 26, 1921. Serial No. 517,879.

To all whom it may concern:

Be it known that I, FRANK NOSSEK, a citizen of the United States, and a resident of the city of Chicago, county of Cook, and 5 State of Illinois, have invented certain new and useful Improvements in Apparatus for Compacting Concrete or the like, of which the following is a specification.

This invention relates to apparatus for 10 compacting concrete or the like, and has for its object the provision of apparatus of this character which will alternately raise a receptacle containing wet concrete, and drop same against an unyielding body, so that 15 the concrete is packed into a compact mass, thereby obviating the necessity for tamping or pressing, ordinarily necessary in the preparation of concrete, particularly concrete building blocks.

20 Another object of the invention is to provide means for forming the concrete into blocks or other shapes during the compacting operation.

Other and further objects will appear 25 hereinafter.

The invention consists in the combinations and arrangements of parts hereinafter described and claimed.

The invention will be best understood by 30 reference to the accompanying drawings forming a part of this specification, and in which,

Fig. 1 is a top plan view of the invention,

Fig. 2 is a side elevation of the invention,

35 Fig. 3 is an end view of the invention,

Fig. 4 is a perspective detail view of one of the molding members employed in the invention,

Fig. 5 is a sectional view on line 5—5 of 40 Fig. 2,

Fig. 6 is a sectional view on line 6—6 of Fig. 5, and

Fig. 7 is a modified form of operating means for said apparatus,

45 The invention consists of a frame of any suitable construction. Such frame is preferably formed of parallel longitudinal timbers 1 and 2, which form the base of the frame. Preferably disposed on the upper sides of said timbers 1 and 2, are transverse timbers 3 and 4, the timbers 4 having their

opposite ends fastened to the timbers 1 and 2 by suitable bolts. The ends of the timbers 3 may be fastened to the ends of the timbers 1 and 2 by any suitable means, but I preferably employ bolts 5, each of which is threaded at one end to receive a nut thereon, and provided with a collar 6 a suitable distance from the opposite end for binding the members together, the extremities of the 60 bolts 5 forming upstanding studs 7. Mounted to normally rest on the timbers 3 and 4 is a platform 8, which is provided adjacent its corners with apertures having disposed thereabout guide plates 8', such apertures 65 and guide plates being adapted to loosely and movably engage the studs 7.

Preferably mounted on the platform 8, are longitudinally extending channel bars 9, such bars being held in position on said 70 platform by any suitable means, clamps 10 being shown. Channel bars 11 are preferably disposed between the ends of the bars 9, and held in position therebetween in a manner hereinafter set forth, the channel 75 bars 9 and 11 together forming a rectangular bed.

Within the bed formed by the channel bars 9 and 11, I preferably mount a plurality of angle bars 12, as shown in Fig. 4, 80 such angle bars being longitudinally disposed end to end, to form parallel rows, as shown in Fig. 1. For properly spacing and retaining said bars in position in said bed, I preferably provide members 13, having slots 14 in their opposite faces, adapted 85 to receive therein the ends 15 of adjacent angle bars 12, as shown in Fig. 1, the lower edges of the members 13 being adapted to rest on the edges 16 of the bars 12 as shown 90 in Fig. 6.

For binding the bed and partition members in position, and for retaining the end bars 11 in position, I provide U bolts 17, preferably one for each end of the bed, such 95 bolts extending through the ends of the channel bars 9 on the outside of the bars 11, and being threaded to receive nuts on their ends. Preferably mounted in the bend of each of the U bolts 17, is a lever 18, having 100 a cam head 19 adapted in operative position to abut against the side of the channel bar

9, to force same inwardly so as to securely bind the members together. When the levers are thrown to inoperative position, the adjacent channel bar 9 is free to move enough 5 to permit removal of the members 11, 12, and 13.

- Preferably mounted on the timbers 1 and 2 are suitable bearings 20 in which are journalled opposite ends of shafts 21 and 22.
- 10 Mounted on shaft 21 adjacent the end thereof, is a sprocket wheel 23, and mounted on the end of the shaft 22, is a sprocket wheel 24, there being a chain 25 connecting said sprocket wheels as best shown in Figs. 1 and 15 2. A suitable driving pulley 26 is mounted on the shaft 22 for driving the sprocket wheels and chain when power is transmitted to said pulley through a suitable belt 27 connected to a source of power (not shown).
- 20 Keyed on the shafts 21, 22, are cams 28 and 29, which are adapted to operatively engage suitable rollers 30 mounted in the brackets 31 secured to the under surface of the platform 8. By this arrangement, it will be 25 observed that when power is transmitted to the sprocket wheels 23, 24, the cams will rotate and raise the platform 8 through a contact with the rollers 30, the shape of such cams being such as to cause a sudden dropping of the platform when it has 30 reached the limit of its upward movement, permitting same to forcibly strike against the timbers 3 and 4 of the frame.

In Fig. 7, I have shown a modification of 35 means for vibrating the bed, in this construction there being an arm 31 keyed on a shaft 32, said shaft having mounted thereon, a hand lever 33. A bearing plate 34 is mounted on the platform 35 and is engaged 40 by a suitable roller mounted on the arm 31. By this arrangement, oscillation of the lever will raise and lower the platform in the desired manner.

In operation, the apparatus is arranged as 45 above described, and filled with wet concrete. Power is then transmitted to the cams which raise and drop the platform onto the members 3 and 4, thus shaking down and compacting the concrete thereon. 50 It is usually desirable to shake the platform approximately one-half hour, in order to thoroughly compact the concrete thereon, the concrete then being permitted to set for approximately twelve hours. Then it may be 55 removed from the apparatus, and in approximately twenty-four hours, is ready for handling. By use of my apparatus, a superior product is produced at a great saving of time.

60 While I have illustrated and described the preferred form of construction for carrying my invention into effect, this is capable of variation and modification without departing from the spirit of the invention. I,

therefore, do not wish to be limited to the 65 precise details of construction set forth, but desire to avail myself of such variations and modifications as come within the scope of the appended claims.

Having described my invention what I 70 claim as new and desire to secure by Letters Patent is:

1. An apparatus for compacting concrete comprising a platform; a receptacle mounted on said platform; angle bars disposed 75 end to end in said receptacle and providing bottom and side means forming longitudinal chambers therein; cross pieces having slots in their opposite side faces and disposed between said angle bars for receiving the ends 80 thereof to retain them in position, binding members extending through and connecting said side bars; and means on said members for locking said receptacle in assembled relation substantially as described. 85

2. An apparatus for compacting concrete comprising a platform operatively mounted on a frame; a receptacle mounted on said platform comprising side and end bars; angle bars disposed end to end in said receptacle and forming longitudinal chambers 90 therein; cross members having slots in their opposite faces to receive the ends of said angle bars, and being disposed between said angle bars to properly space same and retain 95 same in position; and U-bolts connecting said side bars; a cam lever mounted on each of said U-bolts for engaging said side bars to lock said receptacle in assembled relation; substantially as described. 100

3. An apparatus for compacting concrete comprising a platform operatively mounted on a frame; a receptacle mounted on said platform comprising side and end bars, said side bars having a flange thereon; clamps 105 mounted on said platform and adapted to engage said flange; angle bars disposed end to end in said receptacle and forming longitudinal chambers therein; cross members having slots in their opposite faces disposed 110 between the ends of said angle bars and resting on same to retain them in position; and U-bolts connecting said side bars; a cam lever mounted on each of said U-bolts for engaging said side bars to lock said receptacle 115 in assembled relation; substantially as described.

4. An apparatus for compacting concrete comprising a platform operatively mounted on a frame; a receptacle mounted on said platform comprising side and end bars, said side bars having a flange thereon; clamps 120 mounted on said platform and adapted to engage said flange; angle bars placed end to end in said receptacle and providing bottom and side members forming longitudinal chambers therein; cross pieces having slots 125 in their opposite side faces to receive the an-

gle bars, and being placed between said angle bars to properly space the same and retain them in position, **U**-bolts connecting said side bars; and a cam lever mounted on each of said **U**-bolts for engaging said side bars to lock said receptacle in assembled relation, substantially as described.

In testimony whereof I have signed my name to this specification in the presence of two subscribing witnesses.

FRANK NOSSEK.
